UNITED STATES PATENT OFFICE

ALEXANDER H. FOSDICK, OF BETHLEHEM, PENNSYLVANIA, ASSIGNOR TO BETHLEHEM STEEL COMPANY

TUYÈRE

Application filed May 21, 1928. Serial No. 279,344.

My invention relates to tuyères for blast furnaces and more especially to the type which has its body water-cooled and its nose portion filled with refractory material for protection from the excessive heat to which tuyères are subjected.

The object of my invention is to provide a two-piece tuyère comprising a plurality of members made of metal having different physical characteristics.

Another object of my invention is to provide a two-piece tuyère, comprising a nose portion and a body portion, the nose portion of which is first filled with refractory material and then fastened to the body portion by suitable fastening means.

A further object of my invention is to provide a tuyère having its nose portion so assembled that it may be replaced, whenever occasion requires.

The novel features of my invention will be more fully understood from the following description and claims taken with the drawings in which:

25 Fig. 1 is a longitudinal section of the tuyère.

Fig. 2 is a cross sectional view taken on the line 2—2.

30 Fig. 3 is a sectional view taken on the line 3—3.

Referring to the drawings the tuyère 10 comprises two portions, a tapering cylindrical body portion 11, which is preferably of copper which has a high coefficient of heat 35 transmission, and a nose portion 12 which is preferably of ferrous metal which is resistant to wear, although other metal may be used for either of the parts to meet requirements. The body portion 11 is provided with an annular passage or chamber 13, through which cooling water is circulated. The outer end of the body 11 is tapped at 14 and 15, to receive water inlet and 40 outlet pipes 16 and 17, respectively.

45 The body 11 is provided at the other end with an annular offset 18 which provides a seat for the nose portion 12 when the tuyère is in its assembled condition. Holes are 50 tapped in the body portion at 19 to receive

means for fastening the nose and the body portions together.

The nose 12 comprises two cylindrical parallel walls 20 and 21 having recesses 22 therebetween and a connecting end portion 23. The outer wall 20 extends a short distance beyond the inner wall 21 and is provided with holes 24 to receive means for fastening the nose to the body. Preferably the recesses 22 are separated by ribs 25 which are cast integral with the walls 20 and 21 and the end portion 23. The ribs 25 terminate short of the inner end 26 of the nose portion 12, and an annular groove 27 is thus formed into which the end 28 of body portion 11 extends when the tuyère is in its assembled condition.

In order to protect the nose portion 12 of the tuyère from the excessive heat to which it is subjected, any well known refractory material 29 is packed in the recesses 22.

The nose portion 12 and the body portion 11 are assembled into a tuyère by placing the nose portion 12 over the end 28 of the body portion 11 until the inner wall 21 of the nose portion 12 rests against the offset 18. The two parts are then fastened together by inserting screws 30 through the holes 24 of the wall 20 of the nose portion and screwing them into the tapped holes 19 of the body 35 11, or these parts may be connected together by any other well known fastening means. The end 28 of the body portion 11 which extends into the groove 27 is now surrounded by the refractory material on one side and the cooling water chamber on the other, thus insuring the protection of this part from excessive heat.

It will thus be seen that I have devised a tuyère having its major portion made of a metal which transmits heat rapidly and having its nose made of a comparatively inexpensive metal, compared to copper, for resisting the wear to which it is subject in the furnace. With this construction the portion 40 of the tuyère which rapidly wears away in service is of comparatively inexpensive material, whereas the more expensive metal forming the body, which constitutes the water chamber, may be utilized again.

While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

5 I claim:

- 10 1. A tuyère comprising a copper body portion, a detachable ferrous metal nose portion, said body portion having an annular water chamber therein, said nose portion comprising spaced inner and outer walls, means integral with said walls forming a closure for the outer end of said nose portion, and means comprising the extremity of the body portion adapted to provide a closure for the inner end of the said nose portion.
- 15 2. A tuyère comprising a copper body portion, a detachable ferrous metal nose portion, said body portion having an annular water chamber therein, said nose portion comprising spaced inner and outer walls, means integral with said walls forming a closure for the outer end of said nose portion, and means comprising the extremity of the body portion adapted to provide a closure for the inner end of the said nose portion.
- 20 3. A tuyère comprising a body portion, a detachable nose portion, said nose portion comprising spaced inner and outer walls, means integral with said walls forming a closure for the outer end of said nose portion, a filling of refractory material between said walls, said refractory material terminating adjacent the extremity of the body portion which contacts with the nose portion.
- 25 4. A tuyère comprising a body portion, a detachable nose portion, said nose portion comprising spaced inner and outer walls, means integral with said walls forming a closure for the outer end of said nose portion and means comprising the extremity of the body portion adapted to provide a closure for the inner end of said nose portion.
- 30 5. A tuyère comprising a body portion, a detachable nose portion, said nose portion comprising spaced inner and outer walls, means integral with said walls forming a closure for the outer end of said nose portion, means comprising the extremity of the body portion adapted to provide a closure for the inner end of said nose portion and means for detachably fastening the body and the nose portions together.

50 In testimony whereof I hereunto affix my signature.

ALEXANDER H. FOSDICK.
